(57) CLAIM

I claim the ornamental design for a computer desk, as shown and described.

DESCRIPTION

FIG. 1 is a perspective view of a computer desk showing my new design;

FIG. 2 is back perspective view thereof;

FIG. 3 is a Front view thereof;

FIG. 4 is a Back view thereof;

FIG. 5 is a Left- side view thereof;

FIG. 6 is a Right-side view thereof;

FIG. 7 is a Top view thereof; and,

FIG. 8 is a Bottom view thereof.

In the drawings, the broken lines show portions of the computer desk that form no part of the claimed design.
